US0D1075904S

(12) **United States Design Patent** (10) **Patent No.:** **US D1,075,904 S**
(45) **Date of Patent:** **** May 20, 2025**

(54) **PRINTER**

(71) Applicant: **Hand Held Products, Inc.**, Charlotte, NC (US)

(72) Inventor: **José Guadalupe Sánchez de la Rosa**, Tlalnepantla (MX)

(73) Assignee: **HAND HELD PRODUCTS, INC.**, Charlotte, NC (US)

(**) Term: **15 Years**

(21) Appl. No.: **29/924,698**

(22) Filed: **Jan. 19, 2024**

Related U.S. Application Data

(62) Division of application No. 29/868,914, filed on Dec. 16, 2022, now Pat. No. Des. 1,018,660.

(51) **LOC (15) Cl.** **18-99**

(57) **CLAIM**

The ornamental design for a printer as shown and described.

DESCRIPTION

FIG. 1 is a perspective view of a printer showing the new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines illustrate portions of the printer that form no part of the claimed design.

1 Claim, 8 Drawing Sheets
